TEMPERATURE RESISTANT EXPLOSIVE CONTAINING TITANIUM AND ALKALI METAL PERCHLORATE

Charles W. Falterman, China Lake, William J. Griffith, Inyokern, and Harold J. Gryting, Ridgecrest, Calif., assignors to the United States of America as represented by the Secretary of the Navy
No Drawing. Filed Mar. 24, 1965, Ser. No. 442,554
5 Claims. (Cl. 149—42)

The invention described herein may be manufactured and used by or for the Government of the United States of America for governmental purposes without the payment of any royalties thereon or therefor.

The present invention relates to temperature resistant explosives and particularly to a high explosive composition which is stable without melting to above 700° F.

Explosives are conveniently divided into two main categories, the high explosive or detonating explosive, and the low explosive or nondetonating explosive which is used as a propellant. High explosives are normally initiated by a blow from a detonator which is the only practical method of providing a shock of sufficient intensity to initiate the severe processes of detonation, whereas propellant or deflagrating explosives are initiated by thermal means such as a flame. Because of the long periods of storage to which high explosives are subjected and because of the adverse conditions to which they may be exposed, explosives must be as stable as possible. In the field of high explosives those containing trinitrotoluene (TNT), cyclotrimethylenetrinitramine (RDX) or cyclotetramethylenetrinitramine (HMX) have a thermal stability in the region of 300–500° F. The present invention is for a heat resistant explosive the components of which have a thermal stability considerably above those known.

It is an object of this invention to provide an explosive for use in the warheads of missiles.

Another object is to provide a composition which has temperature stability above 700° F.

A further object is the provision of an explosive which will support a detonation wave of from 2500 to over 3000 meters per second.

Still another object is to provide a temperature resistant explosive which is relatively economical to manufacture and is comparatively safe to handle.

Many other objects, features and attendant advantages of this invention will become readily appreciated as the same become better understood by reference to the following description.

The present explosive composition which supports a detonation wave of about 3000 meters per second and is thermally stable above 700° F. comprises about one mole of titanium powder and about two moles of powdered potassium perchlorate. The fine powders (less than 20 μ particle size) were screened and dry blended, then loaded into preforms about 4.5 inches in diameter. The composition having a density of about 1.4 g./cc. supported a detonation wave up to 3000 meters per second. Particle size affects the rate of detonation and particles of up to 20 microns proved successful.

One batch of the explosive consisting of 14 percent by weight titanium powder and 86 percent by weight potassium perchlorate exhibited thermal stability to above 700° F., and loaded into a preform five inches in diameter supported a detonation wave of over 3000 meters per second. It did not melt below 800° F. and the standard autoignition temperature was about 850° F.

Another batch comprising 12.5 percent by weight titanium powder and 87.5 percent by weight potassium perchlorate was mixed and loaded into a five inch pre-

2

form. It consistently supported a detonation wave in the range of 2700 to 3000 meters per second and did not melt below 800° F.

It was found that the percentage composition is critical to this invention. A composition containing from 11 to 14 percent by weight titanium is detonatable with potassium perchlorate. Amounts of titanium over 16 percent by weight would burn with a powerful oxidizer such as potassium perchlorate but would not detonate. Other metals and fuels were substituted for the titanium, but failed to support the shock wave under experimental conditions. These materials included magnesium, aluminum, boron and carbon.

Because sodium perchlorate is similar to potassium perchlorate in chemical structure, it may also be used with titanium powder within the same molar ratios established with the potassium perchlorate; namely, two moles of sodium perchlorate to one mole of titanium.

Modifications and variations of the present invention are possible in the light of the above teachings. It is therefore to be understood that within the scope of the appended claims the invention may be practiced otherwise than as specifically described.

What is claimed is:

1. A temperature resistant explosive comprising one mole of titanium and two moles of oxidizer; said oxidizer being a member selected from the group consisting of potassium perchlorate and sodium perchlorate.
2. A temperature resistant explosive comprising the following ingredients:

	Percent by wt.
Titanium	11-14
Potassium perchlorate	86-89

3. A temperature resistant explosive comprising the following ingredients:

	Percent by wt.
Titanium	12.5
Potassium perchlorate	87.5

4. A temperature resistant explosive comprising the following ingredients:

	Percent by wt.
Titanium	14
Potassium perchlorate	86

said titanium and potassium perchlorate consisting of fine particles up to 20 microns in size.

5. A temperature resistant explosive comprising the following ingredients:

	Percent by wt.
Titanium	15
Sodium perchlorate	85
